[57]

ABSTRACT

A lock for a railway hopper car having a hinged door. The lock comprises a pivotable eccentric member to which is pivotably and eccentrically mounted at latch which engages a lug to hold the car door either loosely or tightly closed. The lug is mounted on the door and loosely engages the latch, which is on the door frame, when the door is swung out. Cam surfaces on the latch and lug cause engagement of the latch and lug. The eccentric member can be rotated to draw the door tightly closed. Rotation of the eccentric member engages the latch in a tightly locked, over-center position on the lug, and the latch and eccentric member can be held in the tightly locked position by a pivotable cam lock. Rotation of the eccentric member in the opposite direction disengages the latch from the tightly locked position and further rotation of the eccentric member causes projections on that member and on the latch to abut so as to lift the latch out of engagement with the lug to permit the door to open fully.

HOPPER CAR DOOR LOCK

This invention relates to locks for railway cars and more particularly to locks for hopper car doors.

Heretofore, door locks of various types have been used to retain hopper car doors, or the like, closed. Such locks are subject to heavy loads and abuse but must be operated easily, hold the door tightly closed, and be easily installed. Locks as constructed in the prior art frequently included a hook or latch and a cooperating lug which were secured to the car and its door. Generally, the latch was swingable either upwardly or downwardly and engaged the lug to hold the door closed. Upwardly swingable latches were usually counterbalanced with a heavy weight. Downwardly swingable latches did not need such counterbalance. Some latches had to be moved manually and aligned with the lug before the door could be closed; other latches had to be moved manually away from the lug before the door could be completely opened; and still other locks had to be manually pried shut before the door could be tightly closed. Not only were such manual operations time-consuming but they also exposed the laborer to considerable danger, particularly when the lock or the mechanism operating the latch was located at the bottom of the hopper. Further, such operations were difficult to perform since access to the lock was limited by the low ground clearance.

The prior art locks located at the bottom of the hopper not only reduced ground clearance but also increased the possibility of damage to the mechanism operating the latch due to obstacles in the roadbed over which the car traveled. Such locks have used various crank and toggle mechanisms having long shafts to actuate the latch. Such mechanisms were expensive to build and difficult to install and to maintain.

A lock in accordance with the present invention eliminates the disadvantages of the prior art constructions and comprises an eccentric member on the door frame, a pivotal latch mounted eccentrically on the eccentric member, and a lug on the door, the latch engaging the lug for retaining a door of the car closed. The latch is not counterbalanced and swings downwardly to engage the lug. At no time is it necessary to manually move the latch, since the lock includes means for engaging and disengaging the latch and lug when the eccentric member is rotated. The latch may be disengaged from the lug by rotating the eccentric member in one direction until the latch rises free of the lug. The latch may be loosely engaged with the lug by swinging the door toward its closed position so that the latch slides over and engages the lug. The lock can be tightly closed by rotating the eccentric member in the other direction to press the latch on the lug. The lock may be mounted at the side of the hopper door so that the lock cannot possibly be damaged by striking an obstacle in the roadbed and the lock can be easily operated since there is increased access to the lock. Further, the lock is sturdy and simply built, has few parts, and may be easily secured to the car.

Accordingly, it is a primary object of the present invention to provide a novel and improved lock for holding closed a door of a hopper car, or the like.

A further object of the present invention is to provide a lock of the foregoing character which can be tightly engaged by rotating an eccentric member.

A still further object of the present invention is to provide novel and improved means for engaging and disengaging a latch and lug of a lock of the foregoing character.

These and other objects of the present invention will become apparent from the following description and accompanying figures of the drawings in which:

FIG. 1 is a fragmentary transverse sectional view of a railway hopper car including locks embodying the present invention;

FIG. 2 is an enlarged fragmentary elevational view taken on the line 2-2 of FIG. 1, with the lock shown in a tightly closed position;

FIG. 3 is a view similar to FIG. 2 with the lock shown in a loosely closed position;

FIG. 4 is another view similar to FIG. 2 with the lock shown in a released position;

FIG. 5 is still another view similar to FIG. 2 with the lock shown in a fully open position;

FIG. 6 is an exploded view of the lock;

FIG. 7 is an enlarged fragmentary view taken on the line 7-7 of FIG. 1 with parts broken away and with parts omitted for clarity; and

FIG. 8 is a cross-sectional view taken along the line 8-8 of FIG. 7.

In FIG. 1 a railway car 11 having hoppers 13 and doors 15 is illustrated. The doors 15 are pivotally supported by hinges 17 on door frames 19 which are secured to the hopper walls. The doors 15 may be held closed by locks 21 having parts thereof, hereinafter described, secured to the frames and the doors. While the locks could be located elsewhere on the hopper, it has been found to be advantageous to locate the locks 21 at the sides of the hoppers because of the increased ground clearance and ease of access to the locks. In this instance, only two locks 21 are needed to secure the two doors 15 since the locks 21 engage a reinforcing beam 23 which is secured to the two doors 15. Each end portion 25 (FIG. 1) of the beam 23 and the door frames 19 have cooperating parts of the locks 21 mounted thereon.

The lock 21, as is better shown in FIG. 6, comprises a mounting plate 27, an eccentric member 31, a latch member 33 having a hook 35 on one end, a lug member 37, and a cam lock 38. The lock 21 is subject to heavy loads and abuse and therefore is preferably formed from a high-strength material such as cast or forged steel. While either the eccentric member 31 and latch member 33 or the lug member 37 could be secured to the door 15, in this instance the lug member 37 is secured to the beam 23 on the doors 15, and the eccentric member 31 and latch member 33 are secured to the associated frame 19.

The mounting plate 27 provides a convenient base on which the eccentric 31, latch 33, and the cam lock 38 can be assembled prior to installation on the car. The mounting plate 27 is generally flat and has three extended ends to which other parts of the lock, hereinafter described, are secured.

In the plate 27 are openings 39 and 41 in which pivot pins 43 (FIG. 6) and 45 are secured. The pivot pins 43 and 45 are generally mushroom-shaped having enlarged heads 47 and 49 which retain the eccentric 31 and cam lock 38 on the pins. While the pins may be removably secured to the mounting plate, in this in-

stance the pins 43 and 45 are welded to the mounting plate 27, as is indicated at 50 (FIG. 8), after the eccentric 31 and cam lock 38 have been installed on the pins. Each of the pins 43 and 45 is hollow, having center openings 51 (FIG. 8) and 53 for fasteners 55 and 57 which also serves to secure the mounting plate 27 to the body of the car 11.

The eccentric member 31 pivots about the pin 43 which is received in a central opening 58 in the eccentric member 31. A boss 59 is located on the eccentric member 31 eccentrically of the opening 58 (FIG. 6) and is formed on the side of the eccentric member 31 nearest the plate 27. The end face or surface 63 (FIG. 8) of the boss 59 abuts the plate 27, and the adjacent face or surface 65 of the eccentric 31 abuts the latch 33. The eccentric 31 loosely abuts the inner side 66 of the head 47 of the pin 43 to retain the eccentric 31 in position. The eccentric 31 has a socket 67 having an enlarged opening 69 therethrough in which a rod 71 (indicated in dashed lines in FIGS. 2, 3 and 4) or other tool may be inserted to facilitate pivoting the eccentric 31 on the pin 43. The socket 67 is inclined with respect to the eccentric 31 to compensate for the fact that the lock 21 is installed on the inclined hopper side.

The latch 33 is downwardly swingable and does not require a counterbalance to assist in moving or aligning the latch for engagement with the lug. The latch 33 pivots about the boss 59 of the eccentric 31 and has on one end a large opening 73 for receiving the boss 59 and, at the opposite end, has the hook 35 for engaging the lug 37. The opening 73 is rotatably engageable with a circumference 74 (FIG. 8) of the boss 59. As is shown in FIG. 8, the latch 33 is contained intermediate the eccentric 31 and the mounting plate 27. Surface 75 (FIG. 8) of the latch 33 abuts the surface 65 of the eccentric 31, and a surface 77 of the latch abuts the mounting plate 27.

The lug 37 has one end having openings 79 secured to the beam end portion 25 by fasteners 82, and the other end of the lug 37 extends beyond the beam end 25 so as to be engageable by the hook 35 of the latch 33. The lug 37 is symmetrical about its mid-plane, indicated by the dashed line 81 (FIG. 6), so that the same latch may be used at either end 25 of the beam 23 by merely reversing the latch top for bottom.

The hook 35 of the latch 33 can be made to engage or disengage the lug 37, to retain the door 15 in, or release the door 15 from, a closed position. To this end, as shown in FIG. 6, the latch 33 has a surface 83 on the inside of the hook 35 which engages a corresponding surface 85 on the interior of an aperture through the lug 37 to hold the door 15 closed. An inclined cam surface 87 on the outer edge of the hook 35 is provided, and a similarly inclined surface 89 is provided on the interior of the aperture of the lug 37. Another similarly inclined cam surface 91 on the exterior of the lug 37 engages the cam surface 87 of the latch 33 to raise the latch over a solid portion 93 of the lug 37 disposed between surfaces 85 and 91 so that the lock 21 may be loosely closed by merely swinging the door 15 against the car 11. When the lock 21 is open, as shown in FIG. 4, the latch 33 rests on pin 88 extending rigidly from the mounting plate 27 in such manner as to keep the latch in proper alignment to close when the lug on the door is swung into engagement with the latch.

The lock 21 can be brought from a loosely closed state to a tightly closed state by rotating the eccentric 31 by means of the rod 71 or other tool, shown in dashed lines in FIGS. 2 to 4. Rotation of the eccentric 31 rotates the boss 59, which has a center indicated at 90 in FIG. 7, about the pin 43. As this rotation occurs, the latch 33 pivots on the boss 59 relative to the eccentric 31. Rotation of the eccentric 31 in the clockwise direction as seen in FIG. 2 causes the hook 35 of the latch 33 to tightly engage the lug 37. As is shown in FIG. 2, the latch 33 has been moved over-center so that the center 90 now lies above the line drawn through the point of contact of the latch 33 and the lug 37, and the center of the pin 55. Any forces on the door 15 that tend to open the door, while the lock is in the over-center position, also tend to retain the latch 33 in the tightly closed or over-center position. Rotation of the eccentric 31 in the counter clockwise direction causes the hook 35 of the latch 33 to loosely engage the lug 37, as shown in FIG. 3. Further rotation of the eccentric 31 will cause a projection or an axially extended finger 95 on the eccentric 31, which extends over the latch 33, to abut a radial projection or extension 97 at 25 the outer edge of the latch 33 and rotate and raise the hook 35 of the latch 33 off the lug 37 so that the door 15 may be swung fully open by the weight of the load in the car 11, as is shown in dashed lines in FIG. 4.

In addition to the over-center locking action 30 described above, the cam lock 38 has been provided to further insure against accidental disengagement of the lock 21. The cam lock 38 has an opening 98 which loosely receives the pivot pin 45, and an outer cam surface 99 is provided on the cam lock 38 for wedging the lock closed. The end 101 of the cam surface 99 has a relatively small radius and the end 103 has a relatively large radius. The cam surface 99 engages an inclined outer surface 105 of the finger 95 on the eccentric member 31 to hold the eccentric member 31 in an over-center locking position, as heretofore described, and also to hold the hook 35 in a lug-engaging position since the finger 95 also abuts the latch 33, as is indicated at 107 in FIGS. 7 and 8. Lugs at the ends 101 and 103 provide surfaces which may be struck, such as by a mallet, to unlock and lock the cam lock.

In FIG. 2, the lock 21 is shown with the latch 33 over-center and tightly engaging the lug 37 with the cam lock 38 engaged to hold the eccentric member 31 and latch 33 in a closed position.

In FIG. 3, the lock 21 is shown in a loosely engaged position. The cam lock 38 has been rotated in the direction indicated by the arrow 109 to release the eccentric 31 and the latch 33. The eccentric 31 has been rotated, as indicated by the arrow 111, so that the latch 33 is no longer over-center locked but only loosely engages the lug 37 and the door 15 has moved slightly away from the frame 19.

In FIG. 4, the lock 21 is shown in the release position 60 where the eccentric member 31 has been further rotated so that the finger 95 on the eccentric abuts the extension 97 on the latch 33 and thus upon still further rotation raises the hook 35 of the latch 33 from the lug 37 so that the door 15 will swing open, as is indicated in dashed lines.

In FIG. 5 the lock is shown in fully open position with the latch 33 resting on the pin 88 to hold the latch 33 in

position for engagement should the door 15 having the lug 37 be swung into place against the car 11. In such case, the cam surface 91 on the lug would strike the cam surface 87 on the latch 33 raising the hook 35 over the solid portion 93 and allowing the hook 35 to drop into the lug aperture to loosely hold the door 15 closed, as in FIG. 3.

After the door 15 has been swung against the car and the latch 33 has engaged the lug 37, the lock 21 can be tightly closed by then rotating the eccentric member 31 and the cam lock 38 to the positions shown in FIG. 2.

It is apparent that a novel and useful hopper car lock has been provided having an eccentric member, a pivotal latch mounted on the eccentric, and a lug which is engageable by the latch. It is further apparent that novel cam surfaces and projections have been provided on the lock to engage and disengage the latch and lug.

What is claimed is:

1. A lock for a door for a railway hopper car, comprising an eccentric member pivotally mounted on the hopper, a latch member pivotally mounted on said eccentric member, a lug mounted on the door, said eccentric member being rotatable in one direction to move said latch member to a position where said latch member engages said lug when the door is swung onto said latch member to hold the door in a loosely closed position, said eccentric member being rotatable in the opposite direction to another position where said latch member holds the door tightly closed, an axially extending finger on one of said members for engaging the other of said members when said latch and eccentric members are in position to hold the door tightly closed, and a cam lock having an outer surface with varying radii pivotally mounted on the hopper adjacent said latch and eccentric members, said cam lock being rotatable into a position with its outer surface wedged against said finger, whereby said cam lock holds said finger of said one member against said other member to hold both said latch and eccentric members in position to hold the door tightly closed.

2. A lock as in claim 1, wherein said finger on said one member abuts against said other member to move said latch member out of engagement with said lug when said eccentric member is further rotated in said one direction.

3. A lock as in claim 2, wherein said finger is on said eccentric member and extends over said latch member.

4. A lock for a door for a railway hopper car, the door being hinged at its top and inclined to swing to a vertical position by its own weight, said lock comprising an eccentric member pivotably mounted on the side of the hopper, a latch member having a hook projecting downwardly and pivotably mounted on said eccentric member, said latch and eccentric members pivoting in generally vertical planes, and a fixed lug mounted on the side of the door, said latch member being movable by rotation of said eccentric member in one direction

to a lug engaging position to loosely hold the door closed, said latch member being movable by rotation of said eccentric member in the opposite direction to an overcenter locked position to tightly hold the door closed, said eccentric and latch members having cooperating projecting means to raise said latch member out of engagement with said lug upon further rotation of the eccentric member in said one direction, said lock including a pin located below said latch for supporting said latch in a position to engage with said lug, said latch member and lug having cooperating cam surfaces to cause said latch member to pivot upwardly over said lug when the door is swung into said latch member, said latch member pivoting downwardly due to its weight to engage said lug to hold the door loosely closed, whereby the door may be opened, loosely closed, and tightly closed by manipulating only the door and said eccentric member.

5. A lock as in claim 4, further comprising a cam lock having an outer surface with varying radii for engaging at least one of said members, said cam lock being pivotally mounted on the hopper adjacent said one member, said cam lock being movable into a position with its outer surface wedged against said one member.

6. A lock as in claim 5, wherein said eccentric member and said cam lock have openings therein, said lock further comprising a mounting plate, a pair of hollow pins extending through said openings in said eccentric member and said cam lock for mounting said eccentric member and said cam lock on said mounting plate, said eccentric member and said cam lock pivoting on said hollow pins, and fasteners extending through said hollow pins and said mounting plate to mount the lock on the hopper.

7. A lock for a door for a railway hopper car, comprising a fixed lug adapted to be secured to the door, a single plate having two openings therein and adapted to be secured to the hopper, a pair of hollow pins secured to said plate and in alignment with said openings in said plate, an eccentric member pivotably mounted on one of said hollow pins, a latch member pivotably mounted on said eccentric member, a pin adjacent said latch member for supporting said latch member in a position to engage with said lug, a cam lock having an outer surface with varying radii and being pivotably mounted on the other of said hollow pins, said latch member being movable by rotation of said eccentric member in one direction to a lug engaging position to loosely hold the door closed, said latch member being movable by rotation of said eccentric member in the opposite direction to an overcenter locked position to tightly hold the door closed, and said cam lock being pivotable to a position for wedging its outer surface against said one member to hold said one member in position, and a pair of fasteners extending through said pair of hollow pins for securing said plate to the hopper.
